PORTABLE FOLDING CHAIR UNIT

Carl W. Sundberg and Montgomery Ferar, Southfield,
Mich., assignors to American Seating Company, Grand Rapids, Mich., a corporation of New Jersey

Filed Apr. 25, 1963, Ser. No. 74,609

Term of patent 14 years

(Cl. D15—8)

Fig. 1

The side not shown is like the side shown while the appearance of the seat and back rest members of the two chairs is identical.

We claim:

The ornamental design for a portable folding chair unit, substantially as shown and described.
